CLAIM

The ornamental design for a point and barrel tip assembly for a writing instrument, as shown and described.

DESCRIPTION

FIG. 1 is a front elevational view of a point and barrel tip assembly for a writing instrument showing my new design;

FIG. 2 is a right side elevational view thereof;

FIG. 3 is a rear elevational view thereof; and

FIG. 4 is an enlarged scale bottom plan view thereof. The environmental structure shown in dotted lines in FIGS. 1-4 is for illustrative purposes only.
